E. V. JOHNSON

FLAT ARCH FLOOR CONSTRUCTION

Filed March 8, 1920

Patented Feb. 26, 1924.

1,484,649

UNITED STATES PATENT OFFICE.

ERNEST V. JOHNSON, OF CHICAGO, ILLINOIS.

FLAT-ARCH FLOOR CONSTRUCTION.

Application filed March 8, 1920. Serial No. 364,017.

To all whom it may concern:

Be it known that I, ERNEST V. JOHNSON, a citizen of the United States, residing in Chicago, in the county of Cook and State of Illinois, have invented a new and useful Improvement in Flat-Arch Floor Constructions, of which the following is a specification.

This invention relates in general to flat arch floor construction and more particularly to constructions of this kind formed of hollow tile. Prior to my invention it has been generally the custom in constructing flat arch tile floors to provide the tile of rhombic shape and set them in place with a key tile at the center of each course. In this arrangement substantially all the tile of the arch have required to be of special form and by reason of the key tile at the center it has been necessary that the tiles of successive courses be arranged in registration as contradistinguished from staggered relation.

My present invention has for its principal object the provision of a flat arch tile floor construction, using the ordinary rectangular tile, and also permitting the staggering of the tile with respect to each other in adjacent courses.

Another and highly important object of the invention is the provision of a flat arch tile floor construction of unusual strength and capable of being laid by the usual labor available for the purpose.

Other objects and advantages of the invention will be apparent as it is better understood from the following description, which taken in connection with the accompanying drawings discloses a preferred embodiment thereof.

Referring to the drawings,

Figure 1 is a partial perspective view of a flat arch tile floor construction laid in accordance with my present invention;

Fig. 2 is an enlarged partial section through the same;

Fig. 3 is a perspective view of a rectangular or cubical tile of ordinary shoe construction;

Fig. 4 is a similar view of a shoe tile used in the floor construction in Fig. 1;

Fig. 5 is a similar view of one of the wedge tile; and

Fig. 6 is a perspective view of one of the blocks beneath one of the girders and structural metal I-beams.

For the purpose of illustrating my present invention I have shown on the drawing in Fig. 1 a part of a flat arch floor construction, in which it is embodied. In this figure reference characters 11 indicate the usual structural metal I-beam members provided as a part of the framework of the building. The flat arch construction is laid between these I-beam members and consists of rectangular or cubical tiles 12, shoe tile 13 at the I-beam and wedge tile 14 between the shoe tile and adjacent rectangular tiles.

The shoe tile is provided with a recess 15 to fit upon the lower adjacent flange 16 of the I-beam and has a face 17 thereabove for disposal at the web of the I-beam. Voids 18 may extend through the tile, if desired. The face of the tile, 19, opposite the face 17 is bevelled or inclined upwardly and toward the face 17.

The rectangular blocks 12 shown in perspective in Fig. 3 are of usual form and consist of faces arranged at right angles to adjacent faces and each parallel with the face opposite. Tile of this character have been frequently used in wall construction and the tile shown on the drawing is the tile in general use in wall building. The tile shown on the drawing may be taken to have dimensions 12 x 12 x 12" and is provided with six voids 21 extending through it and the sides are given the usual scoring or roughening.

The wedge tile 14 is of ordinary baked clay material and has one face 22 arranged at right angles with its top face 23 and the other face 24 angularly disposed with respect to the two faces 22 and 23 so that an end view of the tile is of the right angle triangular form shown at 25.

In constructing the floor, the shoe tile 13 and a course of rectangular tile 12 is laid in position with the usual mortar joints between them. Thereafter the wedge tile 14 are inserted between the shoe tile and the adjacent rectangular tile and driven into place, wedging the tile tightly together and insuring complete bonding between adjacent tile faces. These wedge tile act as keys arranged at the ends and I have found that when thus constructed the course of tile is as strong, where the work is reasonably well done, as is the case where key tile are used at the center of the course and the other tile made of corresponding special form. The course should have a thickness sufficient to

include the theoretical arch, i. e. the line or area along which the load carried is concentrated. This arrangement permits of the staggering of the tile of each course with respect to those adjacent and this is accomplished by starting a course with a full tile and the courses on each side of it with half tile, as may be seen in Fig. 1.

In order to protect the I-beams I provide beneath each a row of rectangular blocks 26 of clay. As is usual the floor body 27 is provided upon the top of the tile and embraces and includes the tops of the I-beams, and ceiling material 28 may be provided beneath the floor. I preferably give to the flat arch the slight crowning, say an inch or so in a span of several feet, in accordance with the custom heretofore existent in the laying of tile flat arches of the special forms mentioned.

While the wedge tile are provided and insure a complete bond between the rectangular tile, it will be manifest that this may be otherwise accomplished.

It is thought that the invention and many of its advantages will be understood from the foregoing description, and it will be apparent that various changes may be made in

the form, construction and arrangement of the parts without departing from the spirit and scope of the invention or sacrificing all of its material advantages, the form hereinbefore described being merely a preferred embodiment thereof.

I claim:

1. A flat arch floor construction, comprising supports, a substantially flat tile body therebetween and comprising blocks of duplicated rectangular hexahedron form and arranged in courses, and wedge blocks between course ends and the supports.

2. A flat arch floor construction comprising arch supports, hollow tile blocks of duplicated rectangular hexahedron form arranged in substantially flat courses and one or more wedge blocks in each said course for arranging the hexahedron blocks in tight relation.

3. A flat arch floor construction comprising girder-engaging tile and tile of rectangular hexahedron form arranged in substantially flat courses extending between oppositely arranged girder-engaging tile and a wedge block inserted between a girder-engaging tile and the adjacent hexahedron tile.

ERNEST V. JOHNSON.
